Term of patent 14 years

Int. Cl. D9—07

U.S. Cl. D9—258

FIG. 1 is a front perspective view of a dispensing valve for pressurized dispensers showing our new design;

FIG. 2 is a side elevational view on a larger scale, the opposite side being a mirror image of the side shown; and

FIG. 3 is a rear elevational view on a still larger scale.

The broken lines in FIG. 1 showing a pressurized dispenser are for illustrative purposes only.

We claim:

The ornamental design for a dispensing valve for pressurized dispensers, as shown and described.
